UNITED STATES PATENT OFFICE.

CARL WAHLER, OF PHILADELPHIA, PENNSYLVANIA.

DESIGN FOR A TEETHING-PLATE.

SPECIFICATION forming part of Design No. 22,987, dated December 26, 1893.

Application filed November 9, 1893. Serial No. 490,483. Term of patent 7 years.

To all whom it may concern:

Be it known that I, CARL WAHLER, a citizen of the United States, residing in the city and county of Philadelphia, State of Pennsyl-

5 vania, have invented and produced a new and original Design for a Teething-Plate, of which the following is a specification, reference being had to the accompanying drawing, forming part thereof.

10 The leading feature of my design for a teething plate is a ring, a handle extending therefrom, and indentations thereon.

In the drawing: A designates a ring, and B a handle which extends from the periphery thereof. On the ring and handle are indentations C. The handle is paddle-shaped.

15 What I claim is—

The design for a teething plate, substantially as shown and described.

CARL WAHLER.
